APPARATUS FOR COMBINING FINELY DIVIDED SUBSTANCES

Henry M. Collins, Vaughan Township, Ontario, and Charles Douglas Wright, Toronto, Ontario, Canada, assignors to Reliable Plastics Company, Limited, Toronto, Ontario, Canada

Application February 3, 1949, Serial No. 74,288

4 Claims. (Cl. 259—11)

1

This invention relates to an apparatus for combining finely divided substances wherein one or more finely divided substances entrained in a gas stream are injected into a finely divided solid, associated with a filter in the form of a curtain of the injected substances directed in a manner about an exhaust port to ensure the removal of the gas from the mixing vessel without entrainment of solid particles.

This application is a continuation-in-part of application Serial No. 687,302, filed July 12, 1943, patented April 4, 1950, No. 2,502,778 in the names of Henry M. Collins and Norman E. Adcock.

It is well known that finely divided powders may be rendered homogeneous by means of a tumbling process. Moreover, it is also known that any liquid which is compatible with one or more of these powders may be sprayed or aspirated into the powder charge at a relatively high rate of introduction, and the liquid will be completely absorbed into the powder particles. The most convenient, and usual method of introducing the compatible liquid is by forming a mist, or spray of the liquid, and injecting this spray into the powder mass in a jet of hot air or hot nitrogen.

Heretofore, the main difficulty has been to provide means for the escape of the injected air or nitrogen without allowing escape of the finely divided powder. Where fine screens or air permeable cloth have been used, it has been found that the dust particles invariably either pass through the filter, or clog the pores completely, stopping the process and possibly causing dangerous pressures in the tumbler.

Similarly where porous packings or composition plates have been used, blocking has invariably occurred. Where large enough interstices have been provided to prevent blocking, considerable amounts of fine powder have been allowed to escape.

It is a particular object of the present invention to provide a filtering curtain which is highly efficient and which involves a gaseous spray which envelopes or touches the marginal edges of the exhaust orifice of an enclosure, the curtain being formed by the introduction of a gas stream into said enclosure by way of an entry port.

With this and other objects in view the invention is applicable to a process for homogeneously combining finely divided substances where at least one of the substances is tumbled in a container or enclosure. Gaseous fluid is injected into the container by means of an inlet port, the container having an exhaust port adjacent the

2

inlet port. The inlet port is designed to inject the gaseous fluid in such manner that an enveloping curtain is formed which touches the marginal edges of the exhaust port thereby forming a wall of gaseous fluid, that is to say said curtain, between the interior of the container and the exhaust passage. Therefore, as gaseous fluid is injected into the container excess gases will be displaced and caused to flow out of the exhaust port, but in order to do so much first pass through said curtain of gaseous fluid whereby entrained particles will be removed from the excess gases to be exhausted.

One general embodiment of the invention is described with reference to the accompanying drawings in which:

Figure 1 illustrates a partial sectional view of a tumbler according to the present invention.

Figure 2 is a face view of the arrangement of the inlet port, that is to say, the plurality of nozzles which direct the injected gaseous fluid to form a filter curtain, this figure also revealing the section line 2—2 of Figure 1.

Figure 3 is a side view on a reduced scale of a tumbler comprising the present invention.

Figure 4 illustrates an enlarged sectional view of one of the double tubes used in the nozzle members.

Figure 5 is a sectional view of a simple type of nozzle which forms a single inlet port providing a curtain of gaseous fluid while injecting the same, the curtain isolating the exhaust port. This figure also shows a different form of conflicting shield.

Figure 6 is a further alternative form of inlet port and exhaust port arrangement.

Referring now more specifically to the drawings, 10 is a barrel-type tumbler having fixed at either end the massive bushings 11, rotatably mounted on the stationary bracket support 12 (see Figure 2) which in turn, slidably mounts the stationary adjustable sleeve 13. An inwardly extending sleeve 14 extends from the bushing 11 to form an inner housing.

A series of double concentric tubes 15 lead from a source of gaseous fluid such as air pressure, and a source of liquid to be introduced to the tumbler and terminate in spray jets or nozzles 16 which are of any variety known, such as used at present for producing a spray of finely divided droplets. In the tubes 15, the air may be passed through the annular space 15a between the walls of the two tubes and the liquid may be passed through the central tube 15b. The tubes 15 are mounted within the annular chamber 17 by pass-

ing through the chamber wall 18 which extends from connection to the sleeve 13 and forms an integral part of the walls 19 of the exhaust passage 20. The remaining wall of chamber 17 is formed by the spaced apart walls 21 which support the sealing ring 22 by means of the separating ring 23 and which are fixed relative to the sleeve 13 and have suitable ports (not shown) to accommodate the conical confining shields 24 which receive the nozzle 16 substantially as indicated.

The flow of gaseous fluid from the inlet port (that is to say, a plurality of nozzles or a single nozzle of suitable design as the case may be) into the container by virtue of the design and position of the particular nozzle or nozzles employed, forms a curtain of gaseous fluid 25 which touches the marginal edge at least, of the exhaust port 26. The shield 27 which extends from the spaced walls 23 by means of the supporting member 28 serves as a means for deflecting the injected gases and directing them in the desired manner. The shape of the shield 27 is determined by the manner in which it is desired that the injected gases be deflected.

Due to pressures built up by the injected substances, a certain amount of finely divided material will tend to pass the sealing ring 22 and ultimately find its way into the chamber 17 unless great pains are taken in the workmanship in the assembly of the components. In order to obviate any difficulties which might arise in this connection, I prefer according to the invention to include the feature of a port 17a in wall 18 communicating with the chamber 17 and having the fitting 17b. Compressed air through this fitting provides pressures in the chamber 17 in excess of the pressures exteriorly thereof associated with the injection of the finely divided substances into the tumbler 10.

Figure 5 illustrates a modified arrangement having a substantially circular shield 29 disposed in the path of the injected gaseous fluid 30 which emanates from the inlet port 31 which is in the form of an annular orifice 32 formed by the outer housing 33 with its depending lip 34 in spaced apart relation to the inner movable member 35, the latter having an exhaust passage 36 communicating with the exhaust port 37. The annular chamber 33 is fed inlet gaseous fluid by way of suitable port 39. As the gaseous fluid is projected from the annular opening or orifice 32, a substantially conical curtain 40 of gaseous fluid is formed, isolating the exhaust port 37. We do not recommend this form of single nozzle mainly because certain difficulties may be encountered in injecting a gaseous fluid along with a powdered material, but where a gaseous fluid alone is injected or a fluid proper, then this particular nozzle device will be found suitable. The present invention, however, does not relate to the specific form of nozzle used for the inlet port, and the development of the nozzle shown in Figure 1 has been found most suitable for all practical purposes.

A further type of nozzle may be used however, substantially as disclosed in Figure 6 wherein the member 41 has a central bore 42 and a co-operating nozzle member 43 designed to cause fluid passing through the annular passage 44 to form a curtain 45 which extends to deflect off the shield 46. The latter is preferably mounted on a tube 47 which in turn mounts the fitting 48, which has a central bore 49 which serves as an exhaust port.

We therefore specify that the terms "nozzle" or "port" in the singular sense, shall also, but not necessarily, include the plural meaning since it is obvious that the curtain of gaseous fluid which we have described may be formed by a plurality of nozzles as in Figure 1, or a single nozzle or entry port as shown in Figures 5 and 6. It is essential that the curtain of gaseous fluid formed isolate the exhaust port so that excess gases will be required to penetrate the curtain in order to find their way to the exhaust port. We also define that the phrase "touching the marginal edges of said exhaust port" shall mean, for the purposes of claiming my invention, that the curtains 25, 40 or 45 touch the marginal edges of the body of material carrying the outlet port or extensions thereof such as the shield 46 in Figure 6.

It will be readily appreciated that the present invention has a wide application in fields other than those indicated, and could be used to advantage in any process where substances are to be homogeneously added to any finely divided powder, and where gases must be exhausted without loss of the powder. For the purpose of general example in this respect, the invention is applicable to the addition of liquid perfumes to talcum or face powder.

The composition of the jet which is introduced from the nozzles obviously may be varied so that it includes one or more materials to be added to the powder charge, or on the other hand, only heated air or nitrogen for drying the powder. In short, without departing from the spirit of the invention, a gas, a mixture of gases, a mixture of gases and liquids, a mixture of gases and finely divided solid particles for the above purpose is obviously within its scope. It includes the addition of any suitable gaseous fluid.

What we claim as our invention is:

1. Apparatus for the treatment of finely divided substances comprising, an enclosure, means for rotating said enclosure, an exhaust port at one end of said enclosure aligned with the axis of rotation thereof, a fluid inlet port including means arranged about said exhaust port and said axis for injecting a curtain of gaseous fluid into said enclosure and directing said curtain to touch the complete periphery of the exhaust port in a manner to isolate the exhaust port from the interior of the enclosure whereby excess gases must pass through the injected curtain of gaseous fluid for exit from the enclosure through said exhaust port.

2. Apparatus for the treatment of finely divided substances comprising, an enclosure, means for rotating said enclosure, an exhaust port for said enclosure, a fluid inlet port for injecting gaseous fluid into said enclosure and including means arranged about said exhaust port and said axis for forming said gaseous fluid into a curtain extending across said enclosure and dividing the same into a primary treating chamber and a secondary chamber wherein the secondary chamber is in direct communication with said exhaust port.

3. Apparatus as claimed in claim 2 and means for supplying compressed air to the secondary chamber at a pressure greater than the pressures in said primary chamber.

4. Apparatus for treatment of finely divided substances comprising the combination of a rotatable enclosure designed to enclose a charge of finely divided substances, an exhaust port at one end of said enclosure aligned with the axis of

rotation thereof, a plurality of injection nozzles arranged about said exhaust port and said axis and forming inlet ports for the introduction of gaseous fluid into said enclosure, said nozzles being thereby disposed to direct the injected gaseous fluid between the charge of finely divided substances and the exhaust port in a manner to cause a curtain of gaseous fluid to be formed which physically touches the outer periphery of the exhaust port to isolate the latter from said charge whereby the injected gaseous fluid forms an effective filter curtain in advance of and across said exhaust port.
